UNITED STATES PATENT OFFICE.

BERT O. RHODES, OF KALAMAZOO, MICHIGAN, ASSIGNOR OF ONE-HALF
TO CHARLES E. MCKINSTRY, OF KALAMAZOO, MICHIGAN.

FISH-LINE REEL.

No. 828,969.

Specification of Letters Patent.

Patented Aug. 21, 1906.

Application filed October 30, 1905. Serial No. 285,031.

To all whom it may concern:

Be it known that I, BERT O. RHODES, a citizen of the United States, residing at Kalamazoo, in the county of Kalamazoo and State of Michigan, have invented certain new and useful Improvements in Fish-Line Reels, of which the following is a specification.

This invention relates to improvements in fishing-line reels.

The objects of this invention are, first, to provide in a fishing-line reel an improved level winding device which is automatically stopped or thrown out of action by the running out of the line; second, to provide in a fishing-line reel an improved level winding device adapted to cause the line to wind upon the reel in such a manner that the liability of back winding, tangling, or knotting of the line is reduced to a minimum; third, to provide in a fishing-line reel an improved level winding device which permits the free unwinding or running out of the line in casting or the like; fourth, to provide in a fishing-line reel an improved level winding device adapted to deliver the line to the reel in winding so that its unwinding therefrom is free and unrestricted; fifth, to provide in a fishing-line reel an improved level winding device adapted for use in connection with practically all of the various structures of reels now in common use; sixth, to provide in a fishing-line reel an improved level winding device which is very simple and economical in structure and durable in use.

Further objects and objects relating to structural details will definitely appear from the detailed description to follow.

I accomplish the objects of my invention by the devices and means described in the following specification.

The invention is clearly defined and pointed out in the claims.

A structure embodying the features of my invention is clearly illustrated in the accompanying drawings, forming a part of this specification, in which—

Figure 1 is a side elevation of a structure embodying the features of my invention. Fig. 2 is a plan of the structure appearing in Fig. 1. Fig. 3 is an enlarged detail cross-section taken on a line corresponding to line 33 of Fig. 1. Fig. 4 is a detail longitudinal section taken on a line corresponding to line 44

of Fig. 2. Fig. 5 is a detail elevation of the cam-cylinder C', showing the structural details thereof. Fig. 6 is a detail vertical section taken on a line corresponding to line 66 of Fig. 3, showing structural details. Fig. 7 is an enlarged detail section taken on a line corresponding to line 77 of Fig. 1, showing the manner of securing the pulley F to the crank.

In the drawings the sectional views are taken looking in the direction of the little arrows at the ends of the section-lines, and similar letters of reference refer to similar parts throughout the several views.

Referring to the drawings, A is a fishing-line reel of the common or any desired construction.

My improved level winding device consists of a frame B, which is clamped on the front of the reel by means of the clamping-plate B'', which engages the front pillar a. The frame B rests against the reel-heads, and the clamping-plate B'' engages behind the pillar a. Bolts b secure the clamping-plates to the frame.

The frame B is provided with a pair of forwardly-projecting arms B', by which the shaft C is carried. A pivot-bearing, as b', is provided for one end of the shaft C, and a bearing b'' is provided for the other end. The bearings b' and b'' are threaded into the arms B'. This enables the adjustment of the bearings to bring them into proper position and also the adjustment of the shaft. On the shaft C is a cam C', which preferably consists of a cylinder having spiral cam-slots therein arranged oppositely with their ends connected.

An arm B'' of the frame B projects forwardly under the cam C' to serve as a support for the line-guiding arm E, which is pivotally secured thereto by a suitable bearing pin, as e. The arm B'' is preferably curved upwardly at the front of the cam C', as clearly appears in Fig. 4.

Arranged through the line-guiding arm E is a pin c'', having a roller thereon arranged in the cam-slot c, so that when the shaft is rotated the line-guiding arm E is swung back and forth in front of the reel-spool A''. The line-guiding arm E is provided with a longitudinal slot e', through which the pin c'' is arranged and in which it is adjustably se-

cured by a suitable nut c'' . By this arrangement the pin c'' may be adjusted back and forth on the arm E, thereby regulating its throw to adjust the same to the particular reel to which the device may be attached.

On the rear end of the line-guiding arm E is an upwardly-projecting line-guide eye E'. This eye E' is preferably T shape in form, having an elongated horizontal portion and a vertical portion, in which the line is free to play, the object of which will appear later.

A pulley D is carried by the shaft C. This pulley is preferably mounted upon a bearing D', which is threaded upon the shaft. The bearing D' is shouldered at one end to retain the pulley, and a ratchet-wheel D'' is provided, which serves to hold the pulley on the bearing. This ratchet-wheel is clamped against the bearing D' by a suitable nut, as d . The nut d also serves as a lock-nut for the bearing D'. On the inside of the pulley D, and arranged to coact with the ratchet-wheel D'' is secured a pawl D'''. This pawl is adapted to normally engage the ratchet-wheel D'', thereby connecting the pulley to the shaft for driving the same.

The pulley D is connected by a suitable band or belt f to a pulley F on the reel-crank A''. Thus connected by the winding of the reel the shaft C is driven, and thereby through the cam C' the line-guiding arm is actuated to guide the line upon the reel-spool A'''.

The pulley F is preferably formed of sheet metal with a web portion and an inwardly-projecting flange-like rim, so that its web portion may be clamped upon the crank-shaft A' on the inside of the crank A'', as clearly appears from Fig. 7. This construction adapts it to be applied to the various forms of reels now in common use.

In the running out of the line in casting or the like the roller c'' of the line-guiding arm engages one of the notches c in the cam, thereby preventing its rotation and holding the line-guiding arm in a central position. The pawl D''' is thrown out by centrifugal force against the stop d' , provided therefor on the wheel D, so that the pawl entirely clears the ratchet D'', thereby obviating undue wear and also the noise that the pawl slipping over the ratchet would make.

The line in running out, as in casting, whips up into the horizontal portion of the eye E and runs back and forth therein in unwinding from the reel, so that the friction on the line is reduced to a minimum.

The movement of the guiding-arm E is so adjusted in relation to the movement of the spool that the line is cross-wound on the spool, as clearly appears from Fig. 2 of the drawings. All portions of the line are thus delivered to the spool, so that it is impossible for the courses of the line to draw or wedge together, which is a great objection to successful casting. When thus cross-wound,

the line is free, so that it is not likely to kink or knot in running out. The eye E' of the guide is so constructed that it does not interfere with the free running out of the line. The liability of back winding or backlashing is reduced to a minimum.

As before stated, my improved line-guide can be readily attached to various styles of fishing-line reels in common use, it only being necessary to attach the pulley F and clamp the frame B to the forward pillar of the reel.

My improved level winder may be adjusted to reels having different lengths of spools by the adjustment of the engaging pin c'' , which regulates the throw of the line-guiding arm. The turning-points of the cam are made abrupt, so that the arm at the ends of its stroke is quickly reversed, thereby preventing the piling up of the line at the ends of the spool.

By my improved line-guide the obstruction or friction in running out the line is reduced to a minimum, thereby enabling longer casts for the same amount of force and skill than would otherwise be possible. The wear on the parts is reduced to a minimum, so that the structure is very durable.

The line-guide is preferably arranged over the cam C', so that its eye is close to the reel-spool, as illustrated. The eye is moved back and forth in front of the spool in a horizontal plane, so that the line is evenly delivered to the spool from end to end, no matter whether it contains a small or a large quantity of line.

Having thus described my invention, what I claim as new, and desire to secure by Letters Patent, is—

1. The combination with a reel, of a crank therefor; a frame; means for detachably securing said frame to the reel; a shaft carried by said frame; a pulley mounted on said shaft; a ratchet-wheel on said shaft; a pawl carried by said pulley, arranged to engage said ratchet-wheel; a pulley on said reel-crank; a connecting-belt for said pulleys; a cylinder on said shaft, having spiral cam-slots therein oppositely arranged and connected at their ends, said slots having centrally-located notches in their rear edges; a line-guiding arm pivotally mounted on said frame; a pin having a roller thereon arranged to engage said cam-slots and adjustably secured to said arm; and a T-shaped line-guide eye on said arm, for the purpose specified.

2. The combination with a reel of a crank therefor; a frame; a shaft carried by said frame; a pulley mounted on said shaft; a ratchet-wheel on said shaft; a pawl carried by said pulley, arranged to engage said ratchet-wheel; a pulley on said reel-crank; a connecting-belt for said pulleys; a cylinder on said shaft, having spiral cam-slots therein oppositely arranged and connected at their ends, said slots having centrally-located

notches in their rear edges; a line-guiding arm pivotally mounted on said frame; a pin having a roller thereon arranged to engage said cam-slots, and secured to said arm; and 5 a T-shaped line-guide eye on said arm, for the purpose specified.

3. The combination with a reel of a crank therefor; a frame; means for detachably securing said frame to the reel; a shaft carried by said frame; a pulley mounted on said shaft; a ratchet-wheel on said shaft; a pawl carried by said pulley, arranged to engage said ratchet-wheel; a pulley on said reel-crank; a connecting-belt for said pulleys; a cylinder on said shaft, having spiral cam-slots therein oppositely arranged and connected at their ends, said slots having centrally-located notches in their rear edges; a line-guiding arm pivotally mounted on said frame; a pin having a roller thereon arranged to engage said cam-slots, and adjustably secured to said arm; and a line-guide eye on said arm, for the purpose specified.

4. The combination with a reel, of a crank therefor; a frame; a shaft carried by said frame; a pulley mounted on said shaft; a ratchet-wheel on said shaft; a pawl carried by said pulley, arranged to engage said ratchet-wheel; a pulley on said reel-crank; a connecting-belt for said pulleys; a cylinder on said shaft, having spiral cam-slots therein oppositely arranged and connected at their ends, said slots having centrally-located notches in their rear edges; a line-guiding arm pivotally mounted on said frame; a pin having a roller thereon arranged to engage said cam-slots, and secured to said arm; and a line-guide eye on said arm, for the purpose specified.

5. The combination with a reel, of a crank therefor; a frame; means for detachably securing said frame to the reel; a shaft carried by said frame; a pulley mounted on said shaft; a ratchet-wheel on said shaft; a pawl carried by said pulley, arranged to engage said ratchet-wheel; a pulley on said reel-crank; a connecting-belt for said pulleys; a cylinder on said shaft, having spiral cam-slots therein oppositely arranged and connected at their ends; a line-guiding arm pivotally mounted on said frame; a pin arranged to engage said cam-slots, and adjustably secured to said arm; and a T-shaped line-guide eye on said arm, for the purpose specified.

5. 6. The combination with a reel, of a crank therefor; a frame; a shaft carried by said frame; a pulley mounted on said shaft; a ratchet-wheel on said shaft; a pawl carried by said pulley, arranged to engage said ratchet-wheel; a pulley on said reel-crank; a connecting-belt for said pulleys; a cylinder on said shaft, having spiral cam-slots therein oppositely arranged and connected at their ends; a line-guiding arm pivotally mounted on said frame; a pin arranged to engage said

cam-slots secured to said arm; and a T-shaped line-guide eye on said arm, for the purpose specified.

7. The combination with a reel, of a crank therefor; a frame; means for detachably securing said frame to the reel; a shaft carried by said frame; a pulley mounted on said shaft; a ratchet-wheel on said shaft; a pawl carried by said pulley, arranged to engage said ratchet-wheel; a pulley on said reel-crank; a connecting-belt for said pulleys; a cylinder on said shaft, having spiral cam-slots therein oppositely arranged and connected at their ends; a line-guiding arm pivotally mounted on said frame; a pin arranged to engage said cam-slots, adjustably secured to said arm; and a line-guide eye on said arm, for the purpose specified.

8. The combination with a reel, of a crank therefor; a frame; a shaft carried by said frame; a pulley mounted on said shaft; a ratchet-wheel on said shaft; a pawl carried by said pulley, arranged to engage said ratchet-wheel; a pulley on said reel-crank; a connecting-belt for said pulleys; a cylinder on said shaft, having spiral cam-slots therein oppositely arranged and connected at their ends; a line-guiding arm pivotally mounted on said frame; a pin arranged to engage said cam-slots secured to said arm; and a line-guide eye on said arm, for the purpose specified.

9. The combination with a reel, of a crank therefor; a shaft; a pulley mounted on said shaft; a ratchet-wheel on said shaft; a pawl carried by said pulley, arranged to engage said ratchet-wheel; a pulley on said reel-crank; a connecting-belt for said pulleys; a cylinder on said shaft, having spiral cam-slots therein oppositely arranged and connected at their ends, said slots having centrally-located notches in their rear edges; and a pivoted line-guiding arm having a projection arranged in said cam-slots, and a T-shaped line-guiding eye thereon, for the purpose specified.

10. The combination with a reel, of a crank therefor; a shaft; a pulley mounted on said shaft; a ratchet-wheel on said shaft; a pawl carried by said pulley, arranged to engage said ratchet-wheel; a pulley on said reel-crank; a connecting-belt for said pulleys; a cylinder on said shaft, having spiral cam-slots therein oppositely arranged and connected at their ends, said slots having centrally-located notches in their rear edges; and a pivoted line-guiding arm having a projection arranged in said cam-slots, and a line-guiding eye thereon, for the purpose specified.

11. The combination with a reel, of a crank therefor; a shaft; a pulley mounted on said shaft; a ratchet-wheel on said shaft; a pawl carried by said pulley, arranged to engage said ratchet-wheel; a pulley on said reel-

- crank; a connecting-belt for said pulleys; a cylinder on said shaft, having spiral cam-slots therein oppositely arranged and connected at their ends; and a pivoted line-guiding arm having a projection arranged in said cam-slots, and a T-shaped line-guiding eye thereon, for the purpose specified.
12. The combination with a reel, of a crank therefor; a shaft; a pulley mounted on said shaft; a ratchet-wheel on said shaft; a pawl carried by said pulley, arranged to engage said ratchet-wheel; a pulley on said reel-crank; a connecting-belt for said pulleys; a cylinder on said shaft, having spiral cam-slots therein oppositely arranged and connected at their ends; and a pivoted line-guiding arm having a projection arranged in said cam-slots, and a line-guiding eye thereon, for the purpose specified.
13. The combination with a reel, of a shaft; a pawl-and-ratchet driving connection for said shaft; a cam-cylinder on said shaft, having spiral cam-slots therein oppositely arranged and connected at their ends, said slots having centrally-located notches in their rear edges; and a pivoted line-guiding arm having a projection arranged in said cam-slots, and a T-shaped line-guiding eye thereon, for the purpose specified.
14. The combination with a reel, of a shaft; a pawl-and-ratchet driving connection for said shaft; a cam-cylinder on said shaft, having spiral cam-slots therein oppositely arranged and connected at their ends, said slots having centrally-located notches in their rear edges; and a pivoted line-guiding arm having a projection arranged in said cam-slots, and a line-guiding eye thereon, for the purpose specified.
15. The combination with a reel, of a shaft; a pawl-and-ratchet driving connection for said shaft; a cam-cylinder on said shaft, having spiral cam-slots therein oppositely arranged and connected at their ends; and a pivoted line-guiding arm having a projection arranged in said cam-slots, and a T-shaped line-guiding eye thereon, for the purpose specified.
16. The combination with a reel, of a shaft; a pawl-and-ratchet driving connection for said shaft; a cam-cylinder on said shaft, having spiral cam-slots therein oppositely arranged and connected at their ends, said slots having centrally-located notches in their rear edges; and a line-guide having a projection arranged in said cam-slots, for the purpose specified.
17. The combination with a reel, of a crank therefor; a shaft; a pulley mounted on said shaft; a ratchet-wheel on said shaft; a pawl carried by said pulley, arranged to engage said ratchet-wheel; a pulley on said reel-crank; a connecting-belt for said pulleys; a cam on said shaft having a stop thereon; and a pivoted line-guiding arm arranged to be actuated by said cam, for the purpose specified.
18. The combination with a reel, of a crank therefor; a shaft; a pulley mounted on said shaft; a ratchet-wheel on said shaft; a pawl carried by said pulley, arranged to engage said ratchet-wheel; a pulley on said reel-crank; a connecting-belt for said pulleys; a cam on said shaft; and a pivoted line-guiding arm arranged to be actuated by said cam, for the purpose specified.
19. The combination with a reel of a shaft; a pawl-and-ratchet driving connection for said shaft; a cam on said shaft having a stop thereon; and a pivoted line-guiding arm arranged to be actuated by said cam, for the purpose specified.
20. The combination with a reel of a cam; connections for driving said cam upon the winding of said reel; a line-guide arranged to be actuated by said cam; and means for automatically locking said cam upon the unwinding of the reel, for the purpose specified.
21. The combination with a reel, of a cam; connections for driving said cam upon the winding of the reel; a line-guide arranged to be actuated by said cam; and means for locking said cam upon the unwinding of the reel, for the purpose specified.
22. The combination with a reel, of a line-guide; connections for actuating said line-guide upon the winding of said reel; and means for automatically stopping said line-guide upon the unwinding of said reel, for the purpose specified.
23. The combination with a reel, of a line-guide; connections for actuating said line-guide upon the winding of said reel; and means for stopping said line-guide upon the unwinding of said reel, for the purpose specified.
24. The combination with a reel, of a line-guide having a T-shaped eye, for the purpose specified.
